CAP FEEDING APPARATUS

William D. Bell, Columbus, Ohio, assignor to
Anchor Hocking Glass Corporation, Lancaster,
Ohio, a corporation of Delaware

Original application April 8, 1939, Serial No.
266,913. Divided and this application Decem-
ber 12, 1939, Serial No. 308,864

4 Claims. CL 226—88.1

My invention relates to cap feeding apparatus. It has to do, more particularly, with apparatus for feeding caps from a source of supply into position to be engaged by the upper ends of containers to be sealed thereby which are moved along by a conveyor.

One of the objects of my invention is to provide cap feeding apparatus of the type indicated which is very simple but very effective.

Another object of my invention is to provide cap feeding apparatus of the type indicated which may be easily and quickly adjusted so that it may be used with caps of various diameters and thicknesses.

Another object of my invention is to provide a cap feeding device of the type indicated of such a nature that the caps will be fed in a single line in edge-to-edge relationship and there will be no danger of one cap riding up on the adjacent cap causing clogging of the device.

Another object of my invention is to provide cap feeding apparatus of the type indicated which will feed the cap into position to be engaged by the container but there will be no danger of the cap leaving the device until it is engaged by the upper end of the container.

Another object of my invention is to provide a cap feeding device of the type indicated in the preceding paragraph which is of such a nature that when the container engages the cap and tends to withdraw it from the cap feeding device, there will be no danger of the container being upset.

This application is a division of my co-pending application Serial No. 266,913, filed April 8, 1939, and directed to Method and apparatus for sealing containers.

The preferred embodiment of my invention is illustrated in the accompanying drawings wherein similar characters of reference designate corresponding parts and wherein:

Figure 1 is a top plan view of a container sealing machine having my cap feeding device associated therewith.

Figure 2 is a view mainly in longitudinal section but partly in side elevation of the machine shown in Figure 1.

Figure 3 is an enlarged perspective view, partly broken away, showing my cap feeding and applying device.

Figure 4 is a side elevational view showing the lower portion of the cap feeding device.

Figure 5 is a plan view of the structure shown in Figure 4.

Figure 6 is a side elevational view of a slightly modified form of cap feeding device.

With reference to the drawings, I have illustrated a machine of the type disclosed in my co-pending application S. N. 266,913. This machine comprises a table 1 which supports a conveyor unit 2 on its upper end. A cap feeding and applying unit 3 and a sealing head unit 4 are supported above the conveyor unit.

The conveyor unit 2 is described in detail in said co-pending application. As disclosed in said application, the conveyor unit 2 is driven continuously from an electric motor 35.

As described in said application, the containers are placed indiscriminately on the conveyor and are moved in the direction of the arrow by the conveyor. My invention is not limited to any particular type of container and cooperating cap but for illustrative purposes I have shown a container which has at its upper end a reduced portion 31 adapted to receive a cap 38. The cap preferably embodies a substantially disk-like portion 39 which has a depending annular skirt 40.

After the containers are positioned on the conveyor, they are first carried between a pair of fingers 42. These fingers will serve to center the containers on the conveyor belt in the manner described in my said co-pending application.

The containers are then carried by the conveyor to the cap feeding and applying unit 3. The cap feeding and applying unit is illustrated best in Figures 3, 4 and 5 and comprises a downwardly inclined and curved runway or chute 50. The chute 50 is composed of a pair of spaced angle members 51.

These angle members 51 are inclined downwardly and their lower ends are curved to such an extent that the lower portions thereof are substantially horizontal and almost parallel with the conveyor. The caps are adapted to rest on the members 51, the members 51 being spaced properly so that the caps will bridge such space. The members 51 may be adjusted towards and away from each other so that the chute is adaptable to caps of varying diameters. For this purpose the members 51 are carried by blocks 52 having threaded openings formed therein through which a shaft 53 passes that has oppositely threaded portions cooperating with the blocks.

This shaft 53 is rotatably carried in bearings secured to bracket members 54. The shaft 53 may be rotated by a knurled knob 55 keyed on the end thereof. The shaft is so mounted in the bearings that it will not move longitudinally. Thus, when the shaft 53 is rotated by means of the knob 55, the members 51 will be moved towards and away

from each other so that the chute can be adjusted to fit caps of any size.

It will be apparent that the caps will lie flat on the members 51 and will slide down the chute in edge-to-edge relationship. In order to prevent one cap from riding upon the adjacent cap, I provide a member 56 which is spaced slightly above the members 51 and extends parallel thereto. This member 56 has a flat lower surface which will be almost in contact normally with the top surfaces of the caps and which will prevent them from riding up onto each other. This member 56 is rigidly carried by a bar 57 which has its ends secured to brackets 58. These brackets 58 have collars 59 which are disposed on the upper ends of vertical posts 60. The collars 59 may be adjusted up or down on the post 60 and held in adjusted position by tightening setscrews 61. This will vary the distance between members 56 and 51. Thus the chute may be adjusted for caps of different thickness as well as for caps of different diameters. The brackets 54 which carry the shaft 53 are also provided with collars 62 disposed on the posts 60 and which may be held in adjusted position thereon by means of setscrews 63. Thus, the members 51 may also be raised or lowered as a unit.

As indicated in Figure 5, each of the members 51 is provided at its lower end with a finger 64 pivoted at 65 to a bracket 66 attached to the side of members 51. The outer end of each of these fingers 64 is provided with an inwardly directed portion 67 which carries a depending portion 67b adapted to engage the edge of the lowermost cap as it leaves the chute. A spring 67a is associated with the pivot point 65 and tends to force the fingers 64 inwardly into engagement with the cap. It will be apparent from Figure 5 that the member 56 terminates a short distance upwardly from the lower ends of the members 51. This member 56 carries at its lower end a finger 68 (Figure 4) which is pivoted to a lug formed on the top thereof as at 69. The finger 68 extends beyond the lower end of member 56 and a depending portion 70 disposed a short distance above the extreme lower ends of members 51. A stop member 71 in the form of a setscrew is provided on the finger and engages the member 56 to limit downward movement of the lower end of the finger. A spring 72 has its lower end connected to the rear end of the finger 68 and its upper end connected to a bracket 73 which is also secured to the member 56. This spring tends to throw the lower end of the finger 68 downwardly and, as stated before, this movement is limited by the stop 71. As indicated in Figure 4, this stop 71 is normally so adjusted that the portion 70 of the finger will almost contact with the rear portion of the cap as it leaves the chute. However, it will not contact with the cap unless the rear portion of the cap tends to tilt upwardly.

The lower end of the cap chute also has a flexible rubber roller 74 associated therewith. This roller is positively driven and will bear upon the top of the lowermost cap as the cap is withdrawn from the cap chute and will aid in the withdrawal of the cap from the chute. This roller is keyed on a transversely extending shaft 75. The outer ends of this shaft are rotatably mounted in bearing members 76. These bearing members 76 are carried on the forward ends of arms 77. These arms 77 are carried adjacent their rear ends on outwardly projecting pivot

pins 78 which are secured to the members 51. The rear ends of these members 51 are joined together (Figure 3) by a bar 79 which extends transversely thereof. In order to determine the vertical position of the roller 74, a pair of stop members 80 in the form of setscrews are provided on the members 51. The lower ends of these screws bear against the bar 79. It will be apparent that if these screws are screwed downwardly, it will cause the rollers 74 to be raised and vice versa.

In the operation of this cap-feeding and applying unit, the caps will be fed into the upper end of the chute either manually one by one or automatically from a magazine. They will slide down through the chute by gravity until the lowermost cap assumes a position in which it projects beyond the end of the chute, as illustrated in Figure 4. The lowermost cap will be held from falling out of the runway by the spring-pressed fingers 64 which will contact with the periphery thereof at opposite points slightly in advance of the diameter thereof. The roller 74 will not yet contact with the top of the cap and the portion 70 of finger 68 will also normally not be in contact therewith. It will be noted that the skirt of the cap is thus disposed in a position where it will be contacted by the mouth of the jar or container as it is moved along by the conveyor below the cap chute. The cap feeder as a whole is adjustable to accommodate jars of different height. The soft rubber roller 74 is driven in a manner to be explained later from the driving mechanism of the conveyor belt. It is driven at a rate of speed which is such that the linear speed of the surface of this roller substantially approximates the rate of travel of the conveyor belt. This roller is driven in a clockwise direction (Figure 4) and it serves to bear upon the top of the lowermost cap as this cap is withdrawn from the cap feeder the jar passing beneath the lower end of the chute and engaging the skirt of the cap. This engagement of the roller with the cap helps withdraw the cap and any tendency of the jar to be upset by the resistance to the withdrawal of the cap from the cap feeder is thereby overcome.

In order to drive the roller 74, as indicated, the shaft has a sprocket 81 keyed on one end thereof. A sprocket chain 82 passes around this sprocket. This sprocket chain also passes around a sprocket 83 (Figure 3) keyed on one end of a transverse shaft 84 rotatably carried by the brackets 54. The opposite end of the shaft 84 carries a sprocket 85 which is keyed thereto and which is driven by a sprocket chain 86. The sprocket chain 86 is driven from the conveyor-driving means in a manner to be described subsequently.

It will be apparent that the posts 60 which support the cap-feeding chute are carried at the rear ends of supporting arms 87. These arms 87 extend forwardly parallel with the conveyor and are secured at 88 to a plate 89 which is disposed in parallel relationship to the conveyor and above the conveyor. The manner in which this plate 89 is supported will be described later.

It will be apparent that the cap-feeding and applying means will apply the caps to the upper ends of the containers in such a manner that they will merely rest loosely thereon. It will also be apparent that as the containers pass to the cap-applying means, the fingers 42 properly center them relative to the cap-applying means.

After the caps have been applied loosely to the

containers, they are moved to the sealing head unit 4. This unit 4 is described in detail in my co-pending application. The sealing head unit is supported above the conveyor belt by the plate 89. The plate 89 is supported on vertically disposed posts 105. I have shown three of these posts but any suitable number may be provided. These posts extend through the top of the table on opposite sides of the conveyor belt and are suitably mounted in the openings in the top of the table for vertical sliding movement relative thereto. The lower ends of these posts 105 are threaded as at 106. Cooperating with the threaded portion 106 of each of the posts is a sprocket 107 provided with a threaded opening through which the threaded portion of the post passes. Each of these sprockets is rotatably mounted but is supported on the table in such a manner that it will not move vertically by suitable means. It will be apparent that if the sprockets 107 are rotated the posts 105, which are connected to the plate 89 in such a manner that they will not rotate, will all be moved simultaneously either up or down. This will move the supporting plate 89 up or down. In order to rotate all the sprockets 107 simultaneously they are connected together by a sprocket chain 108. The chain 108 may be moved manually by means of a horizontally disposed rotatable shaft 109 which may be rotated by a crank 110 disposed outside of the housing 6. The shaft 109 is provided with a worm 111 meshing with a worm-gear 112 splined on one of the posts 105. The sprocket 107 on this post is connected to gear 112 by a sleeve 112a. Thus, by merely rotating the handwheel 110 the plate 89 may be raised or lowered.

It will be apparent that raising or lowering the plate 89 will cause the cap-feeding and applying unit 3 to be raised or lowered bodily. This will also cause the sealing heat unit 4 to be raised or lowered bodily. Thus, by merely rotating handwheel 110, the apparatus may be quickly adjusted to accommodate containers of different heights.

In Figure 6, I show a slightly different form of cap-feeding means. In this form the member 56a which is similar to member 56 of Figures 4 and 5 is continued downwardly and is curved the same as the members 51 of the chute. The roller 74a in this instance is not positively driven and is mounted on member 77a similar to member 77 of Figures 4 and 5. This structure will operate substantially the same as that of Figures 4 and 5 with the exception that the container will withdraw the cap without the aid of the positively driven roller.

Although I have described my cap-feeding device in connection with a machine of the type disclosed in my application Serial No. 266,913, it will be understood that it may be used with other machines.

It will be apparent that my cap-feeding device is simple but effective. It can be readily adjusted for caps of various thicknesses and diameters. The lowermost cap is held in position to be engaged by the container in such a manner that there is no danger of its accidentally falling from the device. The caps are fed downwardly through the chute in such a manner that they will not ride up on each other and clog the chute. The lowermost cap may be readily withdrawn from the chute by engagement of the upper end of the container therewith so that there will be no danger of the container being upset.

Various other advantages will appear from the preceding description, the drawings and the following claims.

Having thus described my invention, what I claim is:

1. A cap-feeding device comprising a chute, means for normally maintaining a cap in the end of the chute in position to be engaged by a container moved therebeneath, a continuously moving conveyor for supporting containers and moving them beneath the chute, a roller adapted to contact with the upper surface of said cap as it is withdrawn from the chute, and means for driving said roller at such a speed that the linear speed of the surface of the roller is substantially the same as the speed of movement of the conveyor.

2. A cap feeding device comprising a chute, means for normally maintaining a cap in the end of the chute in position to be engaged by a container moved therebeneath, a movable conveyor for supporting containers and moving them beneath the chute, a roller adapted to contact with the upper surface of said cap as it is withdrawn from the chute, and means for driving said roller at such a speed that the linear speed of the surface of the roller is substantially the same as the speed of movement of the conveyor.

3. A cap feeding device comprising an inclined chute for supporting the caps in edge-to-edge relationship, means associated with the lower end of the chute for normally holding the lowermost cap in such a position that it will be engaged by the upper end of a container moved therebeneath, said means comprising a finger supported at each side of the lower end of the cap chute and projecting forwardly beyond the lower end of the cap chute, said fingers having spring members associated therewith for urging them towards each other so that they will engage the cap beyond the diameter thereof, a presser member associated with the lower end of the chute and disposed substantially at the lower extremity of the chute above the rear portion of the lowermost cap held in position by said fingers, and a roller member associated with the lower end of the chute for engaging the upper surface of the cap during the time it is being withdrawn from the chute by a container, said roller member being disposed at a point ahead of the points where the lowermost cap is engaged by said fingers which is substantially at the forward edge of said cap.

4. A cap feeding device comprising an inclined chute for supporting the caps in edge-to-edge relationship, means associated with the lower end of the chute for normally holding the lowermost cap in such a position that it will be engaged by the upper end of a container moved therebeneath, said means comprising a finger supported at each side of the lower end of the cap chute and projecting forwardly beyond the end of the cap chute, said fingers having spring members associated therewith for urging them toward each other so that they will engage the cap, and a roller member associated with the lower end of the chute for engaging the upper surface of the cap during the time it is being withdrawn from the chute by the container, said roller member being disposed at a point ahead of the point where the lowermost cap is engaged by said fingers which is substantially at the forward edge of said cap.

WILLIAM D. BELL.
